COCKTAIL PICK

Victor J. Bergeron, Orinda, Calif.

Application July 9, 1958, Serial No. 51,711

Term of patent 14 years

(Cl. D44—29)

The rear face of the cocktail pick shown in Figure 1 is plain and unornamented.

I claim:

The ornamental design for a cocktail pick, as shown and described.
